(57) **CLAIM**

The ornamental design for a computer assembly housing, as shown and described.

DESCRIPTION

FIG. 1 is a perspective view of our design for a computer assembly housing;

FIG. 2 is a front elevation view of the design of FIG. 1; FIG. 3 is a side view of the design of FIG. 1, the opposite side being a mirror image thereof; and,

FIG. 4 is a top down plan view of the design of FIG. 1. The broken lines depict portions of the computer assembly housing which form no part of the claimed design. The broken lines showing a person in FIG. 2 depicts environmental structure and forms no part of the claimed design. The unshaded surfaces visible in FIG. 4, as defined by the outermost edge and the inner square feature of the four square columns, form no part of the claimed design.

The dash-dot-dash broken lines in FIGS. 1 and 4 depict the boundary of the claimed design and form no part thereof. References to “side”, “top”, “front”, “rear” and “bottom” in the figure descriptions are not meant to require certain in-use orientation; a computer assembly housing according to the claimed design may be used in any orientation.
